(57) **CLAIM**

The ornamental design for a powered ladder storage apparatus for use with a vehicle, as shown.

DESCRIPTION

FIG. 1 is a top three-quarter perspective illustration embodying our new design;

FIG. 2 is a top plan view;

FIG. 3 is a bottom plan view;

FIG. 4 is an enlarged end view taken from the right in FIG. 1;

FIG. 5 is an enlarged end view taken from the left in FIG. 1;

FIG. 6 is a left side plan view; and,

FIG. 7 is a right side plan view.

The broken lines are for the purpose of illustrating environment and form no part of the claimed design.
